COMMUNICATIONS SYSTEM

William S. Halstead, Purchase, N. Y., assignor, by
mesne assignments, to Farnsworth Television
& Radio Corporation, Fort Wayne, Ind., a cor-
poration of Delaware

Application December 19, 1944, Serial No. 568,835

22 Claims. (Cl. 179—2)

1

This invention pertains to a system for establishing restricted-range radio communications within a predetermined signaling zone or area, and more particularly to a signaling zone or area along a highway, railway track, or other delineated service area or zone within the confines of which effective radio signaling is to be conducted.

The invention also embraces means whereby the useful range of a radio transmitter is extended along a traffic lane in areas where signals from the radio transmitter would otherwise be ineffective, or where communications between a central station and mobile units are to be channelized along selected lanes of traffic or other delineated signaling zones.

An illustrative application of this invention is in the transmission of intelligence to vehicles proceeding through tunnels, steel bridges, city streets or other delineated areas where radio signal intensity from a remote space radio transmitter is subject to appreciable or effectively complete attenuation. It is also possible, by use of the system of the invention, to provide a continued radio service for vehicles without cessation of radio service on entering a tunnel, where normal space radio wave energy becomes ineffective. This continuation of service may be accomplished without need for the operator of the vehicle to make any tuning adjustments in the vehicle receiver when passing from the effective signaling area of the space radio transmitter, such as a conventional broadcasting station, to the localized signaling area of the zone transmitting system within the tunnel or other restricted area where the space radio signals cannot be received.

Another application of the system is in providing means, operable from a central control point, for selectively establishing communications with mobile units within a given traffic communications zone, telephone lines or radio circuits being utilized in carrying intelligence from the central point to a zone transmitter disposed adjacent the lane of traffic within which communications is to be effective, with signal energy from the zone transmitter being held within the limits required in adequately serving the traffic lanes with which it is associated.

Therefore, it is one of the objects of the present invention to provide means for effecting communications with mobile units by use of a primary radio transmitter serving a given area, and one or more zone transmitters disposed adjacent given lanes of traffic or predetermined secondary signaling areas within which signals from the pri-

2

mary radio transmitter are ineffective, each of said zone transmitters having means for restricting signal energy substantially within its associated traffic signaling area.

It is another object of the invention to provide means for extending the communications range of a primary radio transmitter, with respect to mobile units proceeding along a lane of traffic, this extension in communications range being effected by provision of a zone transmitter, or secondary transmitter, and associated receiver, both the zone transmitter and receiver being disposed adjacent the lane of traffic and having means for substantially concentrating emission of signal energy along the traffic lane, whereby the signals transmitted initially by the primary radio transmitter are received and retransmitted along the traffic lane in zones where signal energy cannot be received directly from the primary radio transmitter, this operation being provided without need for change in tuning of the mobile receiver in moving from the area where the signals from the primary radio transmitter are effective into the area where signals from the secondary transmitter are effective.

It is an additional object of the invention to provide means with which intelligence addressed to mobile units may be received by the mobile units on entering a predetermined signaling zone along a lane of traffic, regardless of the frequency to which the receiver of the mobile unit may be tuned prior to entrance into the signaling zone, for radio paging or other services.

It is still another object to provide traffic zone transmitting means whereby prerecorded intelligence addressed to mobile units is automatically transmitted to mobile units on their entrance into a predetermined signaling zone along a lane of traffic, means also being provided for changing the prerecorded intelligence by remote control from a control point, all transmissions on the traffic lane being monitored by a receiver disposed adjacent the traffic lane and having means associated with its audio output circuit for effecting reproduction of the received signals at the central control point.

Another of the objects of the present invention is to provide means for signaling to radio-equipped vehicles proceeding through a tunnel or other conductively shielded enclosure.

Another object of the invention is to provide means for retransmission of an effective radio signal, on either the same frequency or any other desired frequency, to radio-equipped vehicles by means of a restricted-range carrier-wave signal-

ing system extending through a tunnel or other conductively shielded enclosure.

Still another object of the invention is to provide means for broadcasting and/or disseminating special programs or instructions to radio-equipped vehicles operating in a tunnel or conductively shielded area either on a specified frequency in the broadcast spectrum or regardless of the broadcast frequency to which the car radio is tuned.

A further object of the invention is to provide a plurality of transmitters, each tuned to one of the intermediate frequencies corresponding to the various intermediate frequencies employed in the various type of conventional mobile receivers.

An additional object of the invention is to provide means for remotely controlling one or more zone transmitters disposed adjacent a signaling area so that it is possible to directly transmit voice signals to mobile units in said area, and, simultaneously, while transmitting, to record the voice signals for subsequent repetitive reproduction at the conclusion of the recording cycle, the duration of the voice transmission period being substantially equivalent to the period of time required for completion of the recording cycle.

Another object of the invention is to provide a remotely-controlled communications system to simultaneously transmit and record signaling intelligence, with means for obliterating a message previously recorded on the recording apparatus employed in the system, and means for automatically and repetitively transmitting the recorded intelligence within a predetermined signaling area or zone immediately subsequent to the termination of the recording cycle.

A further object of the invention is to provide a plurality of receivers, adjacent a lane of traffic, each tuned to one of the frequencies employed in a given signaling zone on said lane of traffic, with means for connecting an amplifier and a transducer to each of said receivers so that transmissions of different carrier frequencies on the traffic lane may be independently monitored at a central or remote control point.

A further object of the invention is to provide timing means controllable from a central control unit for determining the duration of the recording of intelligence which is to be transmitted to mobile units within a given signaling zone.

Other objects may be and may become apparent from a perusal of the disclosure, and it is to be understood that the invention is not to be limited except by the scope of the subjoined claims.

In the drawings:

Fig. 1 is a diagram of an illustrative application of the system of the invention as employed in providing a communicating service to mobile units in tunnels or in areas where normal radio facilities are ineffective.

Fig. 2 is a block diagram of a multiple-frequency traffic communications system employing a remote control system for functional control of a traffic zone transmitter-receiver combination.

Fig. 3 is a schematic circuit diagram of one form of traffic communications system providing automatic means for recording and retransmitting intelligence addressed to mobile units within a given signaling zone along a lane of traffic.

Fig. 4 is a schematic circuit diagram of one form of a remote control unit for controlling the type of communications unit shown in Fig. 3.

Fig. 5 shows a remote control unit with one form of panel layout and switching controls.

Fig. 6 represents an arrangement of equipment as employed in one application of the system of the invention.

In Fig. 1, the two tunnels 11 are arranged to take care of traffic in opposite directions, each of said tunnels having a dual traffic lane. Moving vehicles on the above-mentioned traffic lanes are represented by 12, 12A, 12B, and 12C.

In a transmitter room 14, at a convenient point, usually at one end of the tunnel are located the zone, or secondary, radio transmitter 16 and the recorder-reproducer unit 17, where the latter is used.

The radio frequency output from the radio transmitter 16 is coupled to the R. F. induction cables 19 and 20 which run the entire length of the tunnel and terminate in their respective terminating units 23 and 24. The recorder-reproducer unit 17 is coupled to the input of the radio transmitter 16.

The zone radio transmitter 16 and the recorder-reproducer unit 17 are controlled by the remote control equipment located in a service building 21, which may be at one of the tunnel approaches, or at any desired location.

A telephone line 25 is used for both the audio and control circuits between the remote control unit 27 in the service building 21 and the transmitter room 14.

The remote control unit 27 located in the service building has associated with it, a microphone 28, an electric phonograph unit 29, a radio receiver 30 with its associated antenna 31, and a loudspeaker 32. By means of control switches on the remote control unit 27, it is possible to transmit direct from the microphone 28, or by means of the electric phonograph unit 29 over the zone radio transmitter 16. Also, it is possible to apply received radio signals from receiver 30 to the control unit 27 and thence to the transmitter 16. Thus, in this system a signal from the originating, or primary, transmitter 34 with its associated microphone 35 and antenna 36 can be received on the zone radio receiver 30 and retransmitted over the zone radio transmitter 16.

The remote control switching system also controls the recorder-reproducer unit 17 so that a message may be recorded on this device at the same time that it is being transmitted, the recorded message being thereafter automatically repeated over the tunnel radio system by means of the recorder-reproducer unit 17 until interrupted by the control operator when he desires to change the recording.

Fig. 2 is a block diagram of one form of the system for transmitting simultaneously on multiple frequencies. In the diagram a remote control unit 41 is located at a desired control point and has associated with it a monitor loudspeaker 42, a microphone 43, a phonograph unit 44, and a radio receiver 45 with its associated antenna 46.

The output from the remote control unit 41 connects through the telephone line 46 to the transmitting control room where are located a selective switching mechanism 48, a line transformer and transfer relays 50, a magnetic recorder-reproducer 51, a group of transmitters 52, 53, 54, and 55, and line coupling unit 56. The radio frequency output from the line coupling unit 56 connects to a transmission line 58, said line extending the entire length of the tunnel and terminating in a terminating unit 60. Included with the transmitters are four monitor

receivers 61, 62, 63, and 64, all having a common pickup coil or antenna 66 and with their audio outputs connected to the automatic selector switch 68. The antenna 66 is coupled loosely to the transmission line 58, and the monitor receivers are each tuned to a corresponding frequency used by transmitters supplying signal energy in the tunnel.

By employing frequencies in the system that correspond to the intermediate frequencies generally used by vehicle radio receivers, it is possible to receive radio signals in tunnels regardless of the carrier frequency to which the vehicle receivers are tuned. As an example, in the system described, three of the transmitters and their corresponding monitor receivers may be tuned to 465, 262 and 175 kilocycles respectively and the remaining transmitter and receiver adjusted to 550 kilocycles or some designated frequency assigned for mobile operation. However, any one of the receivers may, if desired, be tuned to a designated frequency employed by mobile transmitters.

By employing the system described, a radio-equipped mobile unit may receive signals from the system on entering the signal zone regardless of the frequency to which the mobile receiver is tuned through injection of the signals into the I. F. amplifier of the receiver.

In the operation of the system described in Fig. 2 there are four transmitters, each adjusted to a different frequency and transmitting simultaneously. The transmitters will normally transmit information from the magnetic tape recorder-reproducer 51 which continually repeats its message. The timing cycle of the message may be adjusted so that the complete message will be received by a radio-equipped vehicle moving through a tunnel at its maximum allowed speed during the time the vehicle is in the tunnel.

The four monitor receivers 61, 62, 63, and 64 have their outputs coupled to an automatic selector switch 68 of any well-known type which may be controlled by means of any conventional dialing system or other automatic selecting means, the dialing mechanism may be located in the control unit 41 as will be hereinafter described, said dial mechanism controlling the selective switching mechanism 48. Each of the above-mentioned monitor receivers may be individually monitored by the loudspeaker 42 at the remote control point by proper dialing.

The system also provides dialing or switching means which allows a direct transmission over the system from either the microphone 43, the phonograph unit 44, or the re-transmission of a message from the radio receiver 45.

In addition to the above-mentioned operations, switching means are provided for simultaneously transmitting and recording.

For the purpose of showing the operation of one form of the radio transmitter and recorder-reproducer unit, a schematic circuit diagram of a single radio transmitter and recorder-reproducer combination is shown in Fig. 3. In this diagram the telephone line 75 from the remote control equipment connects to the line transformer 76. The line winding of the line transformer 76 is divided so that in addition to the audio circuit, the two control circuits may be operated independent of each other.

The radio frequency section of the transmitter consists of a crystal oscillator tube 78 and its associated output circuit coupled through the capacitor 80 to the power amplifier tube 82 and

its associated output circuit. The output inductance 84 of the power amplifier is coupled through the capacitor 85 to the transmission line 87 which runs the entire length of the tunnel and terminates at its far end in a terminating unit 88.

The audio frequency section of the circuit consists of a high-gain amplifier stage 90, the output of which is coupled to the control grid 91 of the dual triode tube 94, said tube acting as a mixer. The control grid 92 of the dual triode 94 functions as a second input channel to the transmitter and the audio component from the line transformer 76 couples to this half of the tube through the contacts 115 of the relay 112 when energized, and the line-to-grid transformer 95. The mixer stage output is coupled to the power amplifier or modulator tube 96.

The power supply includes a power transformer 98 and a full-wave rectifier tube 99 with its associated filter circuit 99A. The above-mentioned power supply provides heater current for all tubes and a source of E. M. F. for the operation of the relay 113, the obliterating coil 107 on the recorder-reproducer and plate supply voltage for the audio and radio frequency tubes.

The recorder-reproducer 101, or sound storage device, consists of an endless steel tape or wire 102 operating on rollers by means of power supplied by the electric motor 103, and is provided with a pickup coil 105 which normally couples to the grid input of speech input tube 90, a recording coil 106 which is provided for recording intelligence, and obliterating coil 107 which removes recordings previously made on the steel tape. In the process of making a new recording, the obliterating coil 107 is energized by applying voltage from the power supply through the contact 104 on the relay 113, which is energized during this process, resulting in magnetically erasing the previously recorded messages. The recording coil is coupled, through a network 108 and the contact 109 on the relay 113, to part of the output winding of the modulation transformer 97, resulting in a new recording on the tape when speech signals are impressed on the primary winding of the transformer 97 by speech amplifier 96, which also is the modulator of the R. F. power amplifier 82. The recording cycle of the recorder-reproducer, which is determined automatically by timing motor 120, as hereinafter described, is usually of such duration that it will provide a complete transmission of message over not more than the period of time that it takes for a moving vehicle to travel the entire length of the tunnel or signaling zone at its maximum allowed speed.

A monitor receiver 116 is employed for the purpose of picking up and monitoring the recorded transmissions. The antenna 110 connects to the monitor receiver and is loosely coupled to the transmission line 87. The output from the monitor receiver normally is coupled back into the telephone line 75 through the upper contacts of relay 112 and line transformer 76 so that the remote control point may have a check on, or supervise the transmissions made while the recorder-reproducer is operating in the reproducer position.

A loudspeaker 117 is also provided for checking or supervising the transmissions locally in the transmitter room.

The recorder timing or cycling motor 120 is placed in operation by local control switch 120B or by energization of remotely controlled relay 111 and closure of its contacts 111A, as determined from the remote control point, when new

recordings are to be made. Cam 126, attached to the shaft 120A of motor 120, upon its movement when the timing motor is energized closes contacts 122 and thereby keeps the timing motor in operation until the cam makes one complete rotation, during which the steel tape 102 of the recording mechanism 101 goes through one complete recording cycle. Concurrently, as contacts 122 are closed by cam 126, the contacts 121 are closed by cam 124, also on timing motor shaft 120A. Closure of contacts 121 applies energizing voltage to relay 113, thereby placing the electrical circuits of the recording mechanism in the "recording" condition. This is effected by supplying voltage to obliterating coils 107 through relay contacts 104, as previously outlined, connecting signal voltage to recording coils 106 through relay contacts 109, and by grounding control grid 91 of tube 94, thereby rendering ineffective speech amplifier tube 90, connected to the pick-up coil 105, which is used only during reproduction of recorded signals.

Thus, at the end of the recording cycle, as determined by the length of the steel tape or period of operation of timing motor 120, the recording operation, or cycle, is automatically terminated.

Control circuits are arranged in such manner that in normal operation, when no control signal is applied to the telephone line 75, the output of monitor receiver 116 is connected to the telephone line 75 through contacts 115 of relay 112 and line transformer 76, while signals as recorded on steel tape 102 and as picked up by coil 105 are applied to the input of the speech amplifier 90, thereby modulating, through modulator tube 96, the radio transmitter of which power amplifier 82 is the R. F. output stage. If a new recording is to be made, a source of E. M. F. is applied to telephone line 75, as will hereinafter more fully be described, thereby energizing relay 111 and starting timing motor 120 which places the equipment in recording condition as previously described. In order to prevent feedback caused by signals from the monitor receiver 116 being applied to the telephone line 75 when the line is carrying signals from the remote control point to the recording mechanism 101 and transmitter during recording operations, contacts 89, of relay 113, which are closed when relay 113 is energized, apply energizing voltage to relay 112, thereby disconnecting the output circuit of monitor receiver 116 from the line 75 through opening of the upper contacts of relay 112. Closure of contacts 115, which occurs when relay 112 is energized, then applies signal voltage from the remote control point to line-to-grid transformer 95. Contacts 86 on relay 113 are opened with energization of relay 113 and remove a ground connection from grid 92 of mixer tube 94, thereby permitting signal from transformer 95 to be impressed on grid 92, causing modulation of the transmitter and applying the signals to recording coil 106.

If a direct speech transmission is to be made from the remote control point, control voltage is applied to telephone line 75, as will be described in subsequent paragraphs, in such manner that the control voltage appears across the lower half of transformer winding 76, as illustrated in Fig. 3, which then causes energization of relay 114 only. Closure of contacts 123 of relay 114 effects energization of relay 112, thereby disconnecting the output circuit of the monitor receiver from line transformer 76, as described above, and applying

speech signals from the line to line-to-grid transformer 95. During direct speech transmission, signals from the recorder-reproducer 101 are prevented from modulating the transmitter by closure of contacts 119 of relay 114, which effects grounding of control grid 91, of mixer tube 94. Contacts 118 of relay 114, which are opened with energization of relay 114, remove the ground connection from control grid 92 of mixer 94, thereby permitting impression of signals from transformer 95 on grid 92 of mixer tube 94, and causing modulation of the transmitter.

The system covered by the schematic circuit diagram in Fig. 3 therefore renders the same service as that described in Fig. 2 except for the fact that the circuit indicated is for use on a single carrier frequency instead of multiple frequencies.

In Fig. 4 there is shown a schematic circuit diagram of a remote control unit designed to operate with the transmitter until indicated in Fig. 3. In this circuit diagram the line transformer 125 couples to the telephone line 75 which connects to the traffic zone transmitter. The relay 127, when in the de-energized position couples the line transformer 125 to the input transformer 128 of the audio amplifier. The two-stage audio amplifier consists of a triode input stage 130 and a power amplifier stage 131 with the output coupled to the loudspeaker 132. In this arrangement the above-mentioned amplifier and loudspeaker combination is in a position to continually monitor the transmissions from the transmitter, except when the operator desires to make a new recording on the recorder-reproducer, transmit information directly, or effect a retransmission of a signal from a primary radio transmitter within the traffic zone.

The input jack 133 or other suitable switching means allows the use of a desk microphone 134 or a phonograph reproducer 135 in connection with a speech amplifier tube 136, as shown. The speech amplifier consists of a high-gain input stage 136 coupled to a triode output stage 137. The gain control 138 allows proper adjustment of the output of this amplifier, and the decibel meter 140 indicates the proper adjustment of the gain control 138 for a given optimum signal level on telephone line 75, to which output transformer 137A is connected when relay 127 is closed as will be explained in subsequent paragraphs.

A radio receiver 139, connected to antenna 144 and having a suitable output circuit, may be coupled to speech amplifier tube 137 through input jack 141. A carrier-operated relay 147, connected to the radio receiver, may be used as will be described hereinafter to control the operation of the system when it is desired to effect automatic retransmission of a radio signal picked up by the receiver 139.

The power supply for the amplifiers in which tubes 131 and 137 are parts thereof consists of a power transformer 145 which supplies heater current to the amplifier tubes and plate voltage. The full-wave rectifier tube 146 has associated with it a conventional filter system 146A. A pilot light 148 is used to indicate that the power supply is in operation when a suitable source of power such as 115 volts A. C. is applied to the primary of transformer 145 through fuses 142 and switch 143.

In order to permit direct speech transmission from the remote control point through an associated zone transmitter such as is illustrated in Fig. 3, without employing the recorder-repro-

ducer 101 of Fig. 3, a transmitter control switch 154, Fig. 4, is provided in the remote control unit. When this switch is closed, relay 127 is energized, thereby transferring winding 125A of line transformer 125 from the input transformer 128 of amplifier 130 to the output transformer 137A of amplifier 137, and transferring a ground connection from the control grid of amplifier tube 131 to the control grid of amplifier tube 131, in this manner rendering amplifier 131 ineffective and amplifier 137 effective. Concurrently with the energization of relay 127, switch 154 also effects application of relay-control voltage on telephone line 75 through the lower winding 125B of line transformer 125, thereby causing energization of transmitter control relay 114, Fig. 3, at the transmitter end of the telephone line and effecting direct modulation of the transmitter through mixer tube 94 and modulator 96 as previously explained. During each direct transmission, when relay 114 is energized, signals from the recorder-reproducer unit 101 are not impressed on the speech input tube 90, as has been explained heretofore, while signals from the monitor receiver 116 are prevented from appearing on telephone line 75 by the energization of relay 112 whose contacts open the circuit connecting the output of receiver 116 and line transformer 76 as described in prior paragraphs.

When a recording is to be made on recorder-reproducer unit 101, Fig. 3, from the remote control point, momentary contact switch 156, Fig. 4, is depressed long enough to start the recording timing or cycling motor 151, which in the illustrative system effects a complete rotation of shaft 151A in one minute, thereby establishing a predetermined recording period, or cycle, of that duration. Rotation of the shaft 151A of timing motor 151 results in cam 155 operating to close contacts 157 for the illustrative one-minute recording period during which a recording may be made on the recorder-reproducer unit 101 of Fig. 3. As the shaft 151A completes one rotation, the contacts 157 open, as in the position shown in Fig. 4, thereby terminating the operation of motor 151 and preventing the recurrence of another recording cycle until switch 156 is again depressed.

Simultaneously with the above-described timing operation, as cam 155 closes contacts 157, the cam 155' closes the double contact switch 152, the contacts 149 of which close and thereby cause energization of the relay 127, resulting in transferring the line transformer 125 from the input transformer 128 of receiving amplifier tube 130 to the output transformer 137A of speech amplifier tube 137. The closure of contacts 150 on the switch 152 causes a relay control voltage to be applied in series with the upper line winding of line transformer 125, and the corresponding winding of line transformer 76, Fig. 3, thereby energizing relay 111, Fig. 3, and initiating the operation of timing motor 120 (Fig. 3) and the recording cycle of recorder-reproducer 101, Fig. 3. The shape of the cam 155' and spacing of contacts 150 are such that they allow the contacts 150 to open before the motor control cam 126, Fig. 3, has made a complete rotation, thereby removing relay energizing voltage from relay 111 to prevent re-occurrence of the recording cycle and preventing any overlap in the recordings made on the tape 102.

A recording time indicator 158 (Fig. 4) is also attached to the drive shaft 151A so that the op-

erator is provided with visual means of determining the available recording time.

If a radio signal from a central radio station, such as transmitter 34, Fig. 1, is to be retransmitted, or repeated, in the traffic communications zone, the radio signal energy is received by antenna 144, Fig. 4, connected with a radio receiver 139. The audio output circuit of the receiver is connected through plug 141A and jack 141, to the input of amplifier tube 137. Carrier-operated or signal-controlled relay 147, is actuated during effective reception of carrier-wave energy by radio receiver 147. As shown in Fig. 4, closure of the contacts of relay 147 effects energization of relay 127 and applies relay-control voltage to the lower winding 125B of line transformer 125, thus causing retransmission of the received signals by the zone transmitter in the manner previously described. In this manner, signals may be transmitted at relatively high level to mobile units in a given traffic zone along a lane of traffic by retransmission of the original signals by a zone transmitter disposed adjacent the traffic lane. If, as has been described in preceding paragraphs, a designated zone frequency is used in the traffic communications zone, or an intermediate frequency is employed, the signals emitted by the zone transmitter or transmitters will "break" into the mobile receiver without manual tuning adjustment as the vehicle passes through the localized signaling zone even though signals directly from the originating station may be of different frequency or of such low signal intensity as to render them ineffective at points within the traffic signaling zone.

In the event that signals from an originating transmitter, such as 34, Fig. 1, are to be retransmitted by a zone transmitter, such as 16, Fig. 1, on the same, or substantially the same, carrier frequency, then the zone receiving antenna 31 is usually disposed outside of the localized induction signaling field, surrounding the wayside transmission line, such as 20, Fig. 1. In this manner, signals from the originating transmitter 34 may be received on a given frequency, such as F1, to which the receiver 30 is responsive, and the signals will be retransmitted at the same frequency F1 by zone transmitter 16, to which zone receiver 30 is relatively unresponsive by virtue of the location of antenna 31 at a point outside the effective signaling field of zone transmitter 16.

Further discrimination between signal sources, such as transmitter 34 or transmitter 16, with their associated signal emitting means, may be accomplished by use of a loop or other directionally selective antenna in connection with receiver 30. In this instance, the loop or other directional antenna is positioned such that carrier signals from originating transmitter 34 are favored and signals from zone transmitter 16 are discriminated against, thereby facilitating operation of both transmitters on a common carrier frequency without mutual interference between the two signals.

Fig. 5 illustrates one type of remote control unit as illustrated schematically, in part, in Fig. 4, to be employed with systems such as described in the above paragraphs and illustrations of Figs. 1-4, inclusive. Included on the remote control equipment of Fig. 5 is a line-level meter 161, such as a conventional DB meter, and a recording time indicator 162, as is also illustrated by 158, Fig. 4. A push-to-record switch 166, Fig. 5,

schematically illustrated by 156, Fig. 4, is provided as shown.

A loudspeaker, such as 132, Fig. 4, is placed behind the louvers 168, for use in conjunction with a line amplifier such as 131, Fig. 4, which is incorporated in the control unit of Fig. 5, and allows reproduction of signals from the monitor receivers located at the zone transmitting point. The indicator lights 169 and 170 indicate "power-on" and "voice on" operation respectively, the latter corresponding to symbols 148 and 159 of Fig. 4, respectively. A selector dial 160 may be used to actuate a remotely-controlled selective switching mechanism 48, Fig. 2, or automatic selector switch 68, Fig. 2 of any well-known type, making it possible (1) to monitor each traffic zone receiver separately so that individual transmissions from different transmitters in a selected zone can be checked at all times, (2) to permit direct transmission from a zone transmitter 55, Fig. 2, or to effect (3) combined recording and transmitting by means of a recorder-reproducer 51, Fig. 2, or 101, Fig. 3, and associated transmitting equipment, such as 55, Fig. 2, as previously explained. A toggle switch 167, Fig. 5, may be used to select either tone dialing or D. C. dialing in connection with the operation of a selector dial 160, in any well-known dialing circuit. The power circuit, voice input, and line circuit terminals may be connected to the rear of the control unit as is customary practice.

Through the use of a system such as described in the preceding paragraphs, an operator at a central station may, by use of a remote control unit such as described in connection with Figs. 4 and 5, over a single telephone circuit connecting the remote control unit with zone transmitting equipment such as is illustrated in Fig. 3, directly transmit intelligence to a mobile unit proceeding through a given highway, railway or other traffic signaling zone. Also, by use of the recorder-reproducer unit 101, Fig. 3, and associated recording control circuit of Fig. 4, the operator may, by means of relatively short employment of a telephone line, record intelligence at a wayside transmitting point while concurrently transmitting such intelligence to given vehicles in the traffic signaling zone, then effect monitoring of subsequent transmissions while the recorder-reproducer 101 is in the normal reproducing position, so that the transmitted intelligence, which is repetitively transmitted to vehicles as they enter the signaling zone, may be checked at the control point. At the conclusion of a given recording and checking interval, such as a three-minute period, during which the telephone line connection is maintained, the telephone line circuit may be terminated, yet the zone transmitter will continue indefinitely to repeat the transmission of the recorded intelligence to all vehicles proceeding through the zone. In this manner, telephone calls or other intelligence addressed to trucks, buses, taxicabs, private passenger cars, railway trains, or other mobile units may be picked up by the vehicles upon their entry into the traffic communications zone without need to constantly tie up a telephone facility.

Further, through the use of such zone transmitting equipment placed at strategic points along highways or other lanes of traffic, and by the use of a remote control unit such as described in connection with Figs. 4 and 5, the operator may, by using different telephone circuits extending between the remote control point and the different zone transmitters, place a call for mobile

units in any desired traffic signaling zone. A call placed for a given truck proceeding on a certain highway may be transmitted in the communications zone along this highway near the point where the highway enters a given municipality. Thus, a recurrent message addressed to a given truck may ask the driver to call the control station for routing information relative to unscheduled pick-ups or deliveries in the city that the truck is entering, or the message may give all the necessary information and ask the driver to acknowledge its receipt by telephone, or by two-way radio if the truck is radio equipped, as soon as the message is received. The same procedure may be followed in paging drivers of taxicabs, buses, or private cars, particularly those driven by doctors and others who regularly employ their cars in their work. It is pointed out that in the event such a mobile unit is equipped with radio transmitting facilities, one of the wayside receivers, such as 61, Fig. 2, which may be tuned to a frequency employed by mobile transmitters may be used in picking up carrier signals from the mobile transmitter and impressing the received signals on the telephone line such as 46, Fig. 2, for transmission to the central control point where the remote control unit, such as 41, Fig. 2, is installed. In this arrangement of equipment, the output circuit of the wayside receiver 61 may be connected to the telephone line in any well-known manner, or as shown in Fig. 3, where the output circuit of wayside receiver 116 is normally connected with the telephone line 75 except during recording control or direct speech transmission periods.

It may also be pointed out that signals from a particular wayside receiver such as 61, Fig. 2, may be applied selectively to the telephone line 46 through an automatic selector switch 68 of any well-known type, or by means of any suitable selecting switching mechanism, such as 48, Fig. 2, in which event the automatic selector switch 68 would not be required.

Fig. 6 represents a modification of the traffic communications system previously described, and is of particular value in effecting retransmission of radio signals along extended traffic lanes in zones where radio signals initially emitted from a given transmitter require repeating or retransmission. This modification of the system previously described includes an originating transmitter 174 with a microphone 175 and an antenna 176 which may be located at a designated control point along a traffic lane 173 or at other suitable location. The traffic lane 173 is indicated passing through a tunnel 180, where normal space radio wave energy from a space radio transmitter such as 174 becomes ineffective.

To continue the radio service through the tunnel which may be effected on the same carrier frequency, such as F1, originating at transmitter 174, or at a designated zone frequency, such as F2, which may be an intermediate frequency commonly employed in mobile receivers, or other suitable frequency, a receiver 183, responsive to F1, with a suitable antenna 184, is provided near the tunnel approach. The antenna 184 associated with zone receiver 183 is disposed in such manner that it is effective in receiving carrier wave energy of frequency F1 from originating transmitter 174, rendering the receiver 183 responsive thereto. In the event that the retransmission of the signals received from originating transmitter 174 is effected on the same frequency, F1, by means of zone transmitter 183 and trans-

mission line 190, the receiving antenna 184 may be disposed outside of the effective localized induction signaling field surrounding transmission line 190 and zone transmitter 188, thereby rendering the receiver 183 responsive to carrier wave 5 and energy of frequency F_1 from transmitter 174 and relatively unresponsive to carrier wave energy of frequency F_1 from zone transmitter 188. In this manner, mutual interference between signals from originating and repeating transmitters is avoided even though a common frequency is used. Receiver 183 may be provided with a carrier-operated relay circuit 185, as shown by 141, Fig. 4, and an audio circuit 186 for applying received signals to an input circuit of the zone transmitter 15 188, as illustrated in further detail in Fig. 4, where the audio output circuit of the receiver 139 connects by a plug and jack, 141A and 140, respectively, to speech amplifier tube 137. It will be noted that contacts of carrier-operated relay 141, when the relay is energized, shunt switch 154 and thereby apply relay-energizing voltage 20 to telephone line 75, Fig. 4, and transmitter control relay 114, Fig. 3, thus automatically placing the secondary, or zone transmitter, such as 188, 25 Fig. 6, in operation when a carrier signal is received from the primary transmitter 174. The output circuit of the zone transmitter 188 is coupled to an R. F. transmission line 190 which runs along the entire length of the tunnel and terminates in the terminating unit 191, said terminating unit preventing standing waves on the transmission line 190 and thereby effecting 30 a relatively uniform distribution of signal energy along the line. The local microphone 192 is employed for the purpose of local transmissions at the zone transmitter 10, while the local loud-speaker 205 is used for listening purposes at the zone repeater point. In order to extend the radio system at the opposite end of the tunnel, where 40 the termination unit 191 is located, and where signals from transmitters 174 and 188 may be ineffective, a zone receiver 194 at this point is provided with a receiving antenna or other signal pick-up means 193, said antenna being located 45 in the effective signaling field of the transmission line 190, for the purpose of receiving signals emanating from the zone transmitter 188.

The zone receiver 194 (Fig. 6) has a carrier-operated relay circuit 195, similar to that of receiver 183, and an audio output circuit 196, also similar to that of receiver 183 for automatically energizing and modulating its associated zone transmitter 198. A microphone 199 is also provided for local transmissions at the zone transmitter 198. An antenna 201 is connected to the output of the zone transmitter 198 to effect radiation of signal energy within the service area associated with this transmitter.

Thus, a signal from the originating transmitter 174 covers its primary service area and by means of the receiver 183, equipped with a carrier-operated relay, and having the audio output circuit of receiver 183 coupled to the zone transmitter 188, the original signal is relayed automatically along the service area of the tunnel 190, designated as tunnel A, as long as carrier signals are emitted by transmitter 174. The signal is then received by the zone receiver 194, which also is provided with a carrier-operated relay and audio means for energizing and modulating the zone transmitter 198, where the original signal is retransmitted throughout the service area of transmitter 198, thereby resulting in effectively covering an extended service area along

a traffic lane without cessation in service either by the shielding effect of tunnel A by the shielding effect of a mountain through which the tunnel passes and which may produce an ineffective signal in the zone (designated as the service area of zone transmitter No. 2) on the opposite side of the mountain from that in which the originating transmitter 174 is located.

A second tunnel 202, designated as tunnel B, may also be equipped in a manner identical to that of tunnel A and thereby provide a similar extended service for the system on other traffic lanes running through the second tunnel, in the manner described in preceding paragraphs referring to the illustrative system of tunnel 190.

It is pointed out that the R. F. transmission line 190, Fig. 6, as well as the corresponding line in other figures, need not be a special wire or wires installed for the herein described communications purposes. Where roadside wires such as power lines, telephone, and telegraph circuits, or other suitable metallic conductors are present and may be employed in connection with the system of the invention these may be utilized as signal carriers in establishing an induction signaling field for communications purposes, or in conveying carrier signals along lanes of traffic to strategically-located zone receivers such as 194, Fig. 6, and associated zone transmitters, such as 198, Fig. 6. In this manner, relatively low-power inexpensive wayside or mobile transmitting and receiving equipment may be used in effecting traffic lane communications over much greater distances than normally would be the case if a conventional radio communications system were to be utilized.

It will be recognized that the illustrative systems described herein are capable of considerable modification and rearrangement without departing from the spirit and scope of the invention, and it is therefore to be understood that the following claims embrace all such modifications and equivalent arrangements as may fairly be construed to fall within the scope of the invention.

What I claim as new and desire to secure by Letters Patent of the United States is as follows:

1. In an inductive communications system for establishing communications within a predetermined signaling area, a transmitter, a signal conducting means connected to the output of the transmitter for establishing a substantially predetermined signaling area, said signal conducting means being disposed substantially parallel to the desired longitudinal extent of said substantially predetermined signaling area, a receiver, means connected to the input of the receiver and disposed within the effective signaling area for receiving signals impressed upon the signal conducting means, a remote control apparatus having means for modulating and monitoring the transmitter and receiver respectively, and a selective switching mechanism connected between the remote control apparatus and said transmitter and receiver for connecting either the transmitter or the receiver to the remote control apparatus, to the end that the remote control apparatus may be connected to the transmitter for modulating said transmitter or to the receiver for monitoring transmissions in said predetermined signaling area.

2. In an inductive communications system for establishing communications within a predetermined signaling area, a transmitter, a signal conducting means connected to the output of the transmitter for establishing a substantially pre-

75

determined signaling area, a termination unit connected to one end of said signal conducting means to restrict the formation of standing waves thereon, said signal conducting means being disposed substantially parallel to the desired longitudinal extent of said substantially predetermined signaling area, a receiver, means connected to the input of the receiver and disposed within the effective signaling area for receiving signals impressed upon the signal conducting means, a remote control apparatus having means for modulating and monitoring the transmitter and receiver respectively, and a selective switching mechanism connected between the remote control apparatus and said transmitter and receiver for connecting either the transmitter or the receiver to the remote control apparatus.

3. In an inductive communications system for establishing communications within a predetermined signaling area, a transmitter, a signal conducting means connected to the output of the transmitter for establishing a substantially predetermined signaling area, said signal conducting means being disposed substantially parallel to the desired longitudinal extent of said substantially predetermined signaling area, a receiver, means connected to the input of the receiver and disposed within the effective signaling area for receiving signals impressed upon the signal conducting means, a remote control apparatus having means for modulating and monitoring the transmitter and receiver respectively, a selective switching mechanism connected between the remote control apparatus and said transmitter and receiver for connecting either the transmitter or the receiver to the remote control apparatus and a recorder-reproducer device connectable to the transmitter from the remote control apparatus for recording and reproducing the intelligence impressed upon said modulating means.

4. In an inductive communications system for establishing communications within a restricted area, a transmitter, a signal conducting means connected to the output of the transmitter for establishing a substantially predetermined signaling area, said signal conducting means being disposed substantially parallel to the desired longitudinal extent of said substantially predetermined signaling area, a receiver, means connected to the input of the receiver and disposed within the effective signaling area for receiving signals impressed upon the signal conducting means of the transmitter, remote control apparatus having means for modulating and monitoring the transmitter and receiver respectively, a selective switching mechanism connected between the remote control apparatus and said transmitter and receiver for connecting either the transmitter or the receiver to the remote control means, a recorder-reproducer device connectable to the transmitter from the remote control apparatus for recording and reproducing the signals impressed upon said modulating means, and timing means associated with said recorder-reproducer device for establishing a recording cycle of predetermined duration.

5. In a carrier-wave communications system, a plurality of transmitters, a signal conducting means extending for the length of a predetermined signaling zone, a coupling unit for connecting the output of said transmitters to said signal conducting means, a plurality of receivers having means connected to the input thereof for receiving the signals impressed upon the signal conducting means, a remote control unit having

means for modulating and monitoring said transmitters and receivers respectively, and a selective switching mechanism controllable from the remote control unit for connecting said remote control unit with said transmitters for simultaneously modulating same, said selective switching mechanism also being controllable from said remote control unit for selectively connecting independently any one of said plurality of receivers with said remote control unit for monitoring the signal output of each of said receivers.

6. In a carrier wave communications system, a plurality of transmitters, a signal emanating means, a coupling unit for connecting the output circuit of said transmitters to said signal emanating means, a plurality of receivers having means connected to the input thereof for receiving the signals impressed upon the signal emanating means of the transmitter, a remote control unit having means for modulating and monitoring said transmitters and receivers respectively, and a selective switching mechanism controllable from the remote control unit for connecting said remote control unit with all of said transmitters simultaneously and any one of said plurality of receivers independently.

7. In a communications system having a plurality of transmitters, a signal emanating means, a coupling unit for coupling the output of said transmitters to said signal emanating means, a plurality of receivers having means connected to the input thereof for receiving the signals impressed upon the signal emanating means of the transmitter, a remote control unit having at least one signal source for modulating said transmitters and at least one monitoring means for individually monitoring said receivers, and a selective switching mechanism controllable from the remote control unit for selectively connecting said remote control unit with said transmitters or receivers.

8. In an inductive communications system, a plurality of transmitters each tuned to a different frequency, at least one of said frequencies being substantially equivalent to an intermediate frequency employed in the superheterodyne type of radio receiver, a signal emanating means connected to the output of said transmitters, said signal emanating means being disposed for establishing a substantially limited signaling zone, a plurality of receivers each pretuned to respond to one frequency of the various transmitters, signal pickup means connected to the input circuits of said receivers and disposed within the effective signaling zone for receiving signals transmitted within said zone, a remote control means, modulating and monitoring means connected to said remote control means, and a selective switching mechanism for connecting said remote control means to either said transmitters or to said receivers.

9. In an inductive communications system, a plurality of transmitters each tuned to a different frequency, at least one of said frequencies being substantially equivalent to an intermediate frequency employed in the superheterodyne type of radio receiver, a signal conducting means connected to the output of said transmitters, a plurality of receivers, each receiver being tuned to respond to signal energy of a different frequency, signal pick-up means associated with said conducting means for impressing signal energy upon the input of the various receivers, a remote control means, modulating and monitoring means connected to said remote control means, and a

selective switching mechanism for connecting said remote control means to said various transmitters or to said receivers.

10. In an inductive communications system, a plurality of transmitters each tuned to a different frequency, at least one of said frequencies being substantially equivalent to an intermediate frequency employed in the superheterodyne type of radio receiver, signal emanating means connected to the output of said transmitters, said signal emanating means being disposed along a lane of traffic for establishing a substantially predetermined longitudinal signaling zone, a plurality of receivers, each receiver being complementary to one of said transmitters and pretuned to respond only to the frequency of its complementary transmitter, signal pick-up means disposed within the effective signaling zone for receiving said transmitted signals and being connected to the various receivers, a remote control means, modulating and monitoring means connected to said remote control means, and a selective switching mechanism for connecting said remote control means with said transmitters and receivers.

11. In a communications system, a carrier-wave transmitter, signal emanating means connected to said transmitter for establishing a signaling zone within a substantially predetermined area, a receiver, means connected to the input of the receiver and disposed within the signaling zone for receiving carrier-wave signals from said transmitter, remote control apparatus having means for modulating and monitoring the transmitter and receiver respectively, a selective switching mechanism connected between the remote control apparatus and said transmitter and receiver for connecting either the transmitter or the receiver to the remote control apparatus, a recorder-reproducer device connectable to the transmitter from the remote control apparatus for recording the signals impressed upon said modulating means during a recording cycle, timing means associated with said recorder-reproducer device for establishing a recording cycle of predetermined duration, and a second switching means for connecting said recorder-reproducer to the modulating means whereby signals impressed on said recorder-reproducer during the recording cycle are emitted by said transmitter after completion of said recording cycle.

12. In a communications system, a primary radio transmitter operable on a predetermined carrier frequency F_1 and having a carrier-wave radiating means for establishing effective radio signaling within a given service area, a secondary carrier-wave transmitter also operable substantially on carrier frequency F_1 and disposed adjacent a secondary signaling area wherein an effective carrier signal from the primary radio transmitter cannot be received, said secondary carrier-wave transmitter having means associated with the output circuit thereof for establishing a limited-range signaling field effective principally within said secondary service area, a radio receiver tunable to carrier frequency F_1 emitted by said primary radio transmitter and having an antenna disposed to render said receiver responsive to radio wave energy from said primary radio transmitter but not to carrier wave energy from said secondary transmitter, electric circuit means connected between the output circuit of said receiver and the input circuit of said secondary transmitter whereby received signal energy from said primary transmitter may be applied to the input circuit of said secondary transmitter with-

5 out the existence of mutual interference between carrier wave signals from said primary and said secondary transmitters operating substantially on a common frequency.

13. In a communications system, a carrier-wave transmitter, signal emanating means connected to the output of said transmitter for establishing a signaling field within a substantially predetermined signaling area, a carrier-wave receiver disposed adjacent said transmitter and responsive to carrier wave energy from said transmitter, a signal recording and reproducing means disposed adjacent said transmitter and said receiver, electrical circuit means normally connecting a signal output circuit of said recording and reproducing means to the input of said transmitter whereby recorded intelligence is normally emitted by said transmitter, a telephone line, a remote control unit connected to said telephone line, a relay normally connecting said telephone line to an output circuit of said receiver when said relay is de-energized and operable to connect said telephone line to an input circuit of said signal recording and reproducing means when said relay is energized, said remote control unit having a signal transducer and signal source for signal reproducing and recording functions respectively.

14. In a communications system, a primary carrier-wave transmitter operable on a predetermined carrier frequency F_1 and having a carrier-wave radiating means for establishing effective signaling within a given signaling area, a secondary carrier-wave transmitter also operable substantially on carrier frequency F_1 and disposed adjacent a secondary signaling zone wherein an effective signal from the primary transmitter cannot be received, said secondary transmitter having means associated with an output circuit thereof for establishing a limited-range signaling field effective principally within said secondary signaling zone, a radio receiver tunable to carrier frequency F_1 emitted by said primary transmitter and having signal pick-up means for rendering said receiver responsive to carrier wave energy from said primary transmitter but not to said secondary transmitter, electric circuit means connected between the output circuit of said receiver and the input circuit of said secondary transmitter whereby received signal energy from said primary transmitter may be applied to the input circuit of said secondary transmitter without the existence of mutual interference between carrier wave signals from said primary and secondary transmitters operating substantially on a common frequency.

15. In a communications system, a primary radio transmitter operable on a predetermined carrier frequency F_1 and having a carrier-wave radiating means for establishing effective radio signaling within a given service area, a secondary carrier-wave transmitter also operable substantially on carrier frequency F_1 and disposed adjacent a secondary signaling area wherein an effective carrier signal from the primary radio transmitter cannot be received, said secondary carrier wave transmitter having means associated with the output circuit thereof for establishing a limited-range signaling field effective principally within said secondary service area, a radio receiver tunable to carrier frequency F_1 emitted by said primary radio transmitter and having an antenna disposed to render said receiver responsive to radio wave energy from said primary radio transmitter, said antenna also being disposed to

19

render said receiver unresponsive to carrier wave energy from said secondary transmitter, electric circuit means connected between the output circuit of said receiver and the input circuit of said secondary transmitter whereby received signal energy from said primary transmitter may be applied to a signal input circuit of said secondary transmitter without the existence of mutual interference between carrier wave signals from said primary and secondary transmitters operating substantially on a common frequency, and a carrier-operated relay connected to an output circuit of said receiver, said relay having contacts electrically connected to apply electric power to said secondary transmitter when said relay is energized during reception of a carrier signal and to remove power from said secondary transmitter when said relay is de-energized by lack of a received carrier signal from said primary transmitter.

16. In a communications system for relaying communications into and out of an area which is ordinarily not serviceable by a space radio transmitter including, a space radio transmitter having an antenna for radiating radio wave energy effective in a primary service area, a secondary carrier transmitter, signal emanating means connected to the output of said secondary carrier transmitter and being disposed substantially within the area to be embraced by the effective signaling field of said secondary carrier transmitter, a zone radio receiver having antenna means disposed for reception of signals from said space radio transmitter, the signal output circuit of said receiver being connected to the signal input circuit of said secondary transmitter for modulating said secondary transmitter by signal energy received by said radio receiver, relay means connected intermediate said receiver and said secondary transmitter for activating said secondary transmitter when signals are received through said receiver from said space radio transmitter, a second zone receiver, signal pick-up means disposed within the effective signaling field of said secondary transmitter and having one end thereof connected to the input circuit of said second zone receiver, a second space radio transmitter having an input circuit thereof connected to the output circuit of said second zone receiver, relay means connected intermediate said second zone receiver and said second space transmitter for activating said second space transmitter when signals are impressed upon said second zone receiver, and signal emanating means connected to the output of said second space transmitter for transmitting the signals impressed upon the second zone receiver.

17. In a communications system for relaying communications into and out of an area which is ordinarily not serviceable by a space radio transmitter including, a space radio transmitter having an antenna for effecting radiation of radio wave energy within a primary service area, a secondary transmitter, a termination unit, signal emanating means having one end thereof connected to the output of said secondary transmitter and the other end thereof being connected to said termination unit whereby formation of standing wave energy is inhibited, said signal emanating means being disposed substantially within the area to be embraced by the effective signaling field of said secondary transmitter, a first zone radio receiver having antenna means disposed for reception of radio signals from said space radio transmitter, the signal output circuit of said receiver

20

being connected to a signal input circuit of said secondary transmitter for modulating said secondary transmitter by received signals impressed on the input thereof, relay means connected intermediate said receiver and said secondary transmitter for activating the said secondary transmitter when signals are received by said receiver from said primary transmitter, a second zone receiver, signal pick-up means disposed within the effective signaling range of said secondary transmitter and having one end thereof connected to the input of said second zone receiver, a second space radio transmitter having an input circuit thereof connected to an output circuit of said second zone receiver, relay means connected intermediate said second zone receiver and said second space transmitter for activating said second space transmitter when signals are impressed upon the second zone receiver, and signal emanating means connected to an output circuit of said second space transmitter for transmitting the signals impressed upon the second zone receiver.

18. A communications system for relaying communications into and out of shielded areas which are not ordinarily serviceable by a space radio transmitter, comprising, a space radio transmitter having an antenna for effecting radiation of radio wave energy within a primary service area, a plurality of secondary transmitters for serving said shielded areas where radio wave energy from said space radio transmitter is ineffective, a plurality of radio receivers for receiving the signals originating in the space radio transmitter, each of said receivers being connectable to one of said secondary transmitters, relay means connected intermediate each of said secondary transmitters and its complemental receiver for activating said transmitter when carrier wave signals originating in the space radio transmitter are received, and signal emanating means connected to the output of each of said secondary transmitters and being disposed substantially within the shielded areas to be embraced by the effective signal range of each of said secondary transmitters.

19. A communications system for relaying communications into and out of metallically shielded areas which are not ordinarily serviceable by a space radio transmitter comprising, a space radio transmitter having a range for embracing at least a primary service area, a plurality of secondary radio transmitters, a plurality of radio receivers for receiving the signals of the space radio transmitter, one of said receivers being connectable to each of said secondary radio transmitters, relay means connected intermediate each of said secondary transmitters and its complemental receiver for activating said transmitter when signals are received by the receiver from the space radio transmitter, signal emanating means connected to the output of each of said secondary radio transmitters and being disposed substantially within the metallic shielded areas to be embraced by the effective signal range of each of said secondary radio transmitters, and a radio receiver having antenna means disposed for reception of signals from at least one of said plurality of secondary radio transmitters.

20. In an inductive communications system, a transmitter tuned to an intermediate frequency employed in the superheterodyne type of radio receiver, signal emanating means connected to the output of said transmitter, said signal emanating means being disposed for establishing a

21

substantially limited signaling zone, a receiver pre-tuned to respond to the frequency of said transmitter, signal pickup means connected to the input circuit of said receiver and disposed within the effective signaling area for receiving signals transmitted within said zone, remote control means, modulating and monitoring means connected to said remote control means, and selective switching mechanism for connecting said remote control means to either said transmitter or to said receiver.

21. In an inductive communications system, a transmitter tuned to an intermediate frequency employed in the superheterodyne type of radio receiver, signal conducting means connected to the output of said transmitter, a receiver being tunable to respond to signal energy from said transmitter, signal pick-up means associated with said conducting means for impressing signal energy upon the input of said receiver, remote control means, modulating and monitoring means connected to said remote control means,

22

and selective switching mechanism for connecting said remote control means to said transmitter or to said receiver.

22. In an inductive communications system, a transmitter tuned to the intermediate frequency employed in the superheterodyne type of radio receiver, signal emanating means connected to the output of said transmitter, said signal emanating means being disposed along a lane of traffic for establishing a substantially predetermined longitudinal signaling zone, a receiver pre-tuned to respond only to the frequency of the transmitter, signal pick-up means disposed within the effective signaling zone for receiving said transmitted signal and being connected to the receiver, remote control means, modulating and monitoring means connected to said remote control means, and a selective switching mechanism for connecting said remote control means with said transmitter or receiver.

WILLIAM S. HALSTEAD.
